UNITED STATES PATENT OFFICE.

JAMES R. WOODROUGH, OF CINCINNATI, OHIO, ASSIGNOR TO WOODROUGH
& McPARLIN, OF SAME PLACE.

HANDSAW.

SPECIFICATION forming part of Letters Patent No. 257,802, dated May 9, 1882.

Application filed December 14, 1881. (No model.)

To all whom it may concern:

Be it known that I, JAMES R. WOODROUGH, of the city of Cincinnati, county of Hamilton, State of Ohio, have invented certain new and 5 useful Improvements in Handsaws, of which the following is a specification.

This invention relates particularly to meat-saws. Its objects are to provide a convenient means to readily attach and detach the blade, 10 and to tighten or loosen the same in its frame. These objects are accomplished by the means illustrated in the accompanying drawings, in which—

Figure 1 is a side view of a saw embodying 15 my improvements. Fig. 2 is a view of the forward end of a saw, showing the form of tightening device I, adopt for attachment to that end of the saw-frame. Fig. 3 is a full-sized perspective view of the tightening device represented in Fig. 1.

Similar reference-letters represent identical parts in the different views.

A is a bent metal frame, secured in a curved groove in the ordinary handle, B, a part only 25 of which is shown in Fig. 1, the inner curve of the frame and handle being flush with each other.

C is a lever, made preferably of malleable cast metal. It has a groove to receive the end 30 of frame A, to which it is attached by a fulcrum-pin, c, which passes through its overlapping sides and the end of the frame, and is secured in place by riveting. The lower end of the lever C is slit to receive the saw-blade

35 D, and transversely notched to admit the pin a, which passes loosely through the blade. The upper end of piece C is perforated and tapped to receive the screw E, which passes 40 through it and bears against the inner edge of the frame A. By means of the screw the blade may be tightened or relaxed when desired.

It is the intention to provide several blades with each frame, so that while some are being sharpened one may be used, thus making one frame answer where several are now required. 45

In the modification shown in Fig. 2 the screw E' is tapped through the shortened forward end of frame A', and bears against the inner edge of a lever, F, which has its fulcrum in a pin, f, passed through the upper end of the 50 lever and the frame A'. The rear end of frame A' (not shown) is extended down and transversely notched to receive the fastening-pin of the blade, similar to the forward end of the frame A, Fig. 1.

It would be no departure from my invention to shorten the rear end of frame A and to fulcrum the lever upon the handle, thus making the handle a part of the frame. 55

What I claim is—

In a handsaw of the character described, the combination, substantially as hereinbefore set forth, of blade D and handle B with a curved metal frame, one end of which extends to receive the end of the blade and the opposite end shortened to receive a lever which forms a continuation of said frame, a lever fulcrumed upon said shortened end, one arm of said lever adapted to receive one end of the saw-blade and the opposite arm extended opposite the shortened end of the frame, and a screw passing through said arm and bearing against said shortened end to turn said lever on its fulcrum for the purpose of tightening or loosening the saw-blade. 65 70

JAMES R. WOODROUGH.
